METHOD AND APPARATUS FOR CONTROLLING FRACTIONATING COLUMNS

Clarence J. Schilling, Allentown, Pa., assignor to Air Products, Incorporated, a corporation of Michigan

Application May 23, 1949; Serial No. 94,877

7 Claims. (Cl. 62—2)

1

This invention relates to automatic controls for fractionating columns and more particularly to a method of and apparatus for the automatic control of the purity of a product produced in such a fractionating column.

It is well known that the purity of a product from a fractionating column may be controlled by varying the rate at which the product is withdrawn. On increasing the rate of withdrawal, the purity diminishes; on decreasing the withdrawal rate, the purity rises. This is a commonly used step for controlling product purity. The adjustment of the product outlet valve is made manually by the operator guided by observation of some form of purity indicating or recording meter. It would be possible to provide a control over the outlet valve opening which would be responsive directly to purity, as for example by the use of a thermal-conductivity purity meter; however, such instruments are reduced in practical usefulness by high cost and great delicacy of construction.

This invention has as an object the provision of a method and apparatus for the automatic control of the purity of the bottom product produced in fractionating a mixture, by controlling the rate at which the bottom product is withdrawn.

A further object is to control automatically the withdrawal of the bottom product by taking advantage of the wide changes in the temperature differential between different levels in fractionating a mixture.

Another object of the invention is to provide in the fractionation of a mixture control of the purity of the product at the bottom of the column by utilizing changes in the temperature differential between the bottom of the column and another point in the column at a higher level.

These and other objects are accomplished by the present invention wherein one means responsive to changes in temperature is provided at the bottom of a fractionating column where one component is at the maximum purity, and another such means is provided in the neighborhood of a level higher in the column where the concentration of a second component is beginning to drop from a maximum and the concentration of a third and more volatile component is negligible but is beginning to increase, so that changes in the temperature differential between the two levels are utilized to control the rate of withdrawal of the first component and thus stabilize the purity of this component.

While this invention is applicable to the control of the purity of a product obtained in the

2

fractionation of any normally gaseous mixture, it is found especially useful in connection with the fractionation of air, wherein the purity of the oxygen being produced is closely controlled.

For the purpose of this invention, air will be considered as consisting of approximately 20.8% of oxygen, 78.2% of nitrogen and 1% of argon by volume, thus disregarding the minute quantities of the rarer elements which do not affect materially the composition of the products obtained in the separation of the air into oxygen and nitrogen.

Usually no attention is given to the argon content of the air. Argon has a boiling point about 15° C. below that of oxygen and about 10° C. above that of nitrogen. Consequently, in the normal rectification of air, the argon tends to follow the oxygen to the lower levels of the rectifier and thus tends to contaminate the oxygen product.

20 The concentration of the argon in both the liquid and vapors increases materially until a point at a certain level in the rectification column is reached where the argon concentration is at a maximum. In practice, the percentage of argon

25 accumulating at this point in the column is between 7 and 12%.

Since the boiling and dew-curves of argon-oxygen mixtures lie close together, the mixture is more difficult to separate than an oxygen-nitrogen mixture. Thus, on the lower plates of a fractionating column for a tertiary mixture such as air, the separation is between the argon and the oxygen, and only a negligible amount of nitrogen is present. At a level about one third 30 of the way up from the bottom of the column, the percentage of argon on each plate begins to decrease from the maximum concentration, and the percentage of the nitrogen starts to increase. It is this level in the column that is utilized in 35 the present invention for the location of the upper control means.

At constant pressure, the boiling point of liquid oxygen-rich mixture rises with increasing approach to purity in oxygen. If this change in 40 temperature could be directly used to control the setting of the oxygen withdrawal valve, the purity of the oxygen could be directly controlled. This change in temperature of the liquid oxygen in the receiver is not, however, available for 45 directly actuating an oxygen valve control mechanism; first, because it is of very small magnitude, and second, because it is impossible to avoid some small fluctuations in pressure which vary the

50 boiling point of oxygen of constant composition. The effect of changes in column pressure may

be substantially eliminated and the magnitude of the temperature change which follows from a change in composition may be greatly increased by making use of the difference in temperature between the oxygen in the receiver and the liquid on a plate higher up in the column, this plate being at the level at which the change in temperature following from a change in the purity of oxygen in the receiver is at the maximum, that is at the plate where the concentration of the argon is near the maximum but is beginning to drop and a concentration of nitrogen is beginning to appear.

In an air fractionating column, the temperature increases from plate to plate, downwardly, and is at the maximum in the oxygen receiver. The temperature increments from plate to plate are small at the ends of the column where the change in composition from one plate to the next is slight, but at an intermediate point, particularly in the region of maximum argon concentration where the nitrogen concentration is negligible, the increment from plate to plate is relatively large.

At this level, spaced from the oxygen receiver by about one-third the total number of plates, the change in temperature following from a given change in purity of the oxygen in the bottom of the column is from five to ten times as great as the change in temperature in the receiver itself. This temperature differential becomes sufficient to control accurately the width of opening of the oxygen valve, through temperature responsive means located within the column at the two levels, i. e., at the receiver and in the neighborhood of a suitably selected level spaced from it where the concentration of the argon is at a maximum but is just beginning to decrease and the concentration of the nitrogen is negligible but is just beginning to increase.

Certain practical applications of the invention will be described with reference to the attached drawings and the following descriptions thereof, in which:

Fig. 1 is a diagrammatical view of the medial portion of a two-stage fractionating column, illustrating preferred locations for the heat-responsive elements;

Fig. 2 is a diagrammatical view illustrating a form of the invention in which the differential expansions and contractions of two fluids are caused to actuate the needle of an oxygen outlet valve through mechanical linkage;

Fig. 3 is a diagrammatical view illustrating a form of the invention in which fluid expansion is used to actuate the valve needle through an interposed solenoid;

Fig. 4 is a diagrammatical view illustrating a form of the invention in which the expansions of rigid metallic elements actuate the valve stem through mechanical linkage; and,

Fig. 5 is a diagrammatical view illustrating a form of the invention showing a control device which does not depend on expansion to actuate the control elements.

Referring first to Fig. 1, reference numeral 10 indicates the medial portion of a two-stage fractionating column of conventional design, the high pressure section 11 being separated from the low pressure section, of which a fragment is indicated at 12, by a partition plate 13 and a nitrogen condenser 14. The stack of fractionating plates 15 separates oxygen in a desired approach to purity. This liquid collects in a pool 16 surrounding the condenser and is kept constantly

boiling in condensing nitrogen vapor evolved at considerably higher pressure in the high pressure section 11.

A fluid-filled bulb 17 is located at some convenient level in or closely adjacent to oxygen pool 16, preferably a short distance below its normal surface level. A similar fluid-filled bulb 18 is placed on or near a plate higher up in the column, preferably in the region near the maximum argon concentration as described above. These bulbs are connected through capillary tubes 19 and 20 with appropriate parts of a mechanism 21 illustrated in Fig. 2, which will next be described. It will be understood that while the location of the lower bulb in or very close to the liquid oxygen pool is essential, the other bulb may be located on any plate above it, the responsiveness of the apparatus increasing to a maximum at the plate where the argon concentration is at a maximum but is just beginning to decrease and the concentration of the nitrogen is negligible but is beginning to increase, which is about one-third the way up the length of the low pressure column. Above this level, the responsiveness diminishes. Thus, in the specification and claims, the term is used "in the neighborhood of" the level at which the argon concentration is beginning to decrease from a maximum and the nitrogen concentration is negligible but is beginning to increase. This term is meant to include a range of a number of plates wherein the control apparatus will be operative. When originally designing a plant, the level for placing the upper temperature responsive means is calculated for the particular purity of oxygen which the plant is designed to produce. If, however, in operation of the plant, the purity of the oxygen is to be varied, the same upper level can be used to control the rate of withdrawal of the oxygen product. For purities other than those for which the plant was designed, the upper level will still be "in the neighborhood" of the point where the argon concentration is beginning to drop from a maximum and the nitrogen concentration is beginning to increase from a negligible amount. Although the level will not be at the preferred point, the apparatus will still operate satisfactorily and incorporate the advantages of the invention.

In Fig. 2, 22 is a valve body having an orifice 23 in which a tapering needle 24 is reciprocated to vary the width of the annular passage through which oxygen flows. This body is suitably mounted in oxygen withdrawal pipe 25. Oxygen withdrawal pipe 25 may be located either below the liquid oxygen level or above it, for removal of the oxygen as a liquid or as a gas respectively.

A rigid yoke 26 is firmly attached to the oxygen pipe or valve body or otherwise accurately positioned with regard to the latter. Within this yoke are mounted two Sylphon bellows 27 and 28, opposing each other in action. Projections 29 and 30 from the free ends of the bellows engage opposite sides of a lever 31 which is pivoted in one arm of the yoke as at 32. The free end of the lever is linked at slot 33 to a valve stem 34 to which valve needle 24 is attached. If this attachment is by a threaded connection as at 35 the needle may be adjusted manually to find the valve opening which gives the required oxygen purity under normal operating conditions. This is an initial adjustment only, not the operative control.

The capillary tubes 19 and 20 are so connected to the respective bellows that the expansion of fluid in the lower bulb 17 tends to move the needle

downwardly or in a closing direction while the expansion of fluid in upper bulb 18 tends to move the needle upwardly and thus increase the valve opening. Assuming the fluid in each bulb to be a gas under compression, an increase in the purity of the oxygen in pool 16 causes its temperature to rise and thus causes the pressure in bulb 17 and bellows 27 to increase. At the same time, a much greater increase in temperature occurs in the liquid surrounding bulb 18 and the pressure in this bulb and in bellows 28 increases to a greater degree. As these pressures act on opposite sides of lever 31, the force tending to lift the valve stem and increase the width of the flow opening is a function of the temperature difference between the two levels in the column. With suitable proportioning of bulb capacities, initial gas pressures and linkages, all of which are subject to exact calculation in any given instance, the changing value of the temperature difference between the two levels may be caused to move the valve stem and needle automatically to new positions at which the changed rate of flow through the valve offsets the change in purity of the oxygen and thus causes it to return to its original value.

When there is a decrease in the purity of the oxygen in pool 16, its temperature drops and thus causes the pressure in bulb 17 and bellows 27 to decrease. At the same time, a much greater decrease in temperature occurs in the liquid surrounding bulb 18 and the pressure in this bulb, and in bellows 28, decreases to a greater degree. As these pressures act on opposite sides of lever 31, the force tending to lower the valve stem and decrease the width of the flow opening is a function of the increase in temperature difference between the two levels in the column. This changing value of the temperature difference between the two levels causes the valve stem and needle to move downwardly so that the new position of the needle decreases the rate of flow and thus the purity of the product is increased.

In the use of gas filled bulbs, any gas which remains in the gaseous phase at the lowest temperatures occurring in this portion of the column and at the pressure to which the bulbs are filled may be utilized, as for example nitrogen, hydrogen or helium. Or a liquid which does not freeze at column temperature and which has a reasonably low vapor pressure at atmospheric temperature, as for example propane or propylene, may be used. If the bulbs are charged with liquid, it is necessary to substitute a resilient element, such as a stiff, open-coil spring, for each of the rigid pins 29 and 30.

A form of indirect actuation of the valve stem by differential temperature changes is illustrated in Fig. 3, in which several of the parts may be identical with similarly numbered parts in Fig. 2. In this form, the valve stem 34 is an extension of the core 36 of a solenoid 37 and is urged downwardly by a spring 38 bearing on a collar 39, the solenoid being spaced from the valve by a rigid yoke 40. In this form, changes in the pressures in the bellows 27 and 28 cause the arm 31 to travel across the contact points of a rheostat indicated at 41, thus varying the amperage of an electrical current and the extent to which the core, and with it the valve stem, are retracted against the downward pressure exerted by the spring.

In the form illustrated in Fig. 4, the expansion and contraction of metallic rods is applied through mechanical linkage to raise and lower

the valve stem. In this figure, 22 indicates only the top of the stuffing box of the valve and 12-12 are fragments of the shell of the column, separated to indicate a wide separation in the column length. A yoke 42 of a metal having a relatively low coefficient of expansion, such as iron or nickel, is fixed to the inner wall of the shell and a rod 43 of a metal having a high coefficient of expansion, such as copper, or aluminum, is attached to the inner end of the yoke and passed through the wall of the shell as through a stuffing box or equivalent 44. A bracket 45 affixed to the outer wall of the shell carries a bell-crank 46 and a projecting arm 47, the latter bearing on the upper end of a spring 48 of which the lower end bears on a collar 49 fixed to valve stem 34. The rod 43 of this unit is positioned in the liquid oxygen pool 16, as at the level indicated for bulb 17 in Fig. 1.

A similar assembly is located on the shell at the level shown for bulb 18 of Fig. 1, but in this unit the bell crank 46A is reversed in position, the arm 47A engaging the lower end of spring 48A and urging valve stem 34 upwardly when rod 43A expands.

The above described structures have the common functions of producing expansion with rising temperature of expansible elements—gaseous, liquid or solid—located respectively at that level in the column at which the oxygen is at the maximum momentary purity and at a higher level at which the column fluids contain less oxygen; of utilizing the expansion and contraction of the lower-lying element to urge the oxygen-withdrawal-control valve in a closing or opening direction, respectively, and of utilizing the expansion and contraction of the higher-lying element to urge the withdrawal-control valve in an opening or closing direction, respectively. This combination of steps takes advantage of the greater degree of temperature change at the higher level to add to the sensitivity of the control and neutralizes any effect on temperature following from pressure changes of normal magnitude within the column.

It will be evident that the utilization of these expansions and contractions may be brought about in many ways and by many devices of which the above described structures are suggestive only.

In the form illustrated in Fig. 5, a control device is shown which does not depend on expansion of a gas, liquid or solid to actuate the control elements. In place of the bulbs 17 and 18 shown in Fig. 1, resistance coils of a material which changes appreciably in resistivity with change in temperature are used. The resistance coils are branched from a current source 52, 53 through lines 19A and 20A and return lines 19B and 20B. Interposed in lines 19B and 20B are opposed minute solenoids 54, 55 which actuate rods 50, 51, which in turn actuate an arm 31 which travels across the contact points of a rheostat 41. Thus, changes in resistance of the resistance coils changes the amount of current flowing through minute solenoids 54, 55 which in turn acting through arm 31 vary the amperage of an electrical current to control a large solenoid linked to the valve as in Fig. 3.

I claim:

1. Apparatus for stabilizing the purity of oxygen collecting in the lower end of an air fractionating column having an oxygen withdrawal line comprising, means sensitive to temperature changes at a level in the column where the oxy-

gen is at the maximum purity, means sensitive to temperature changes at another level in the column in the neighborhood of the point where the argon concentration is beginning to decrease from maximum concentration and the nitrogen concentration is low but is beginning to increase, and means actuated by the first and second claimed means in response to changes in the temperature differential between the two levels to control the rate of the oxygen withdrawal through the withdrawal line.

2. Apparatus for stabilizing the purity of a liquid product collecting in the lower end of a fractionating column for a tertiary mixture of different boiling points which may include inconsequential proportions of additional components, the column having a first component withdrawal valve, comprising, temperature responsive means located in the column at substantially the level of maximum momentary purity of the first component, temperature responsive means located in said column in the neighborhood of a materially higher level where the concentration of the second component is beginning to decrease from a maximum and the amount of the third component is negligible but is beginning to increase, two opposed pressure chambers and a movable element interposed between the chambers and urged in opposite directions by the pressures therein, means operatively connecting the movable element with the valve to open and close the same, and conduits connecting each of the pressure chambers with one of the temperature responsive means, the conduit connections and operative connections being so arranged that an increase in the temperature differential between the two levels results in the actuation of the valve in a closing direction whereas a decrease in the temperature differential between the two levels results in the actuation of the valve in an opening direction.

3. Apparatus for stabilizing the purity of the highest boiling point product of a fractionating column separating mixtures having at least three components of different boiling points, the column having a highest boiling point product withdrawal line, comprising means sensitive to temperature changes at one level in the column where the highest boiling point product is at the maximum purity, means sensitive to temperature changes at a second level in the column in the neighborhood where the concentration of a lower boiling point component is beginning to decrease from maximum and the concentration of a still lower boiling point component is low but is beginning to increase, and means actuated by the first and second claimed means in response to the changes in the temperature differential between the two levels to control the rate of highest boiling point product withdrawal through the withdrawal line.

4. Apparatus for stabilizing the purity of the highest boiling point product of a fractionating column separating tertiary mixtures of different boiling point components, which mixture may include inconsequential proportions of additional components, the column having a highest boiling point product withdrawal line, comprising means sensitive to temperature changes at one level in the column where the highest boiling point product is at the maximum purity, means sensitive to temperature changes at a sec-

ond level in the column in the neighborhood where the concentration of the intermediate boiling point tertiary component is beginning to decrease from a maximum and the concentration of the lowest boiling component is low but is beginning to increase, and means actuated by the first and second claimed means in response to the changes in the temperature differential between the two levels to control the rate of the highest boiling point product withdrawal through the withdrawal line.

5. The method of controlling the rate of withdrawal of the highest boiling point product collecting in a fractionating column in which mixtures having at least three components of different boiling points are separated to stabilize the purity of the highest boiling point product, comprising utilizing the changes in the temperature differential between a level in the column where the highest boiling point product is at the maximum purity and a second level in the column in the neighborhood where the concentration of a lower boiling component is beginning to decrease from maximum and the concentration of a still lower boiling point component is low but is beginning to increase to control the rate of withdrawal of the highest boiling point product.

6. The method of controlling the rate of withdrawal of the highest boiling point product collecting in a fractionating column in which tertiary mixtures of different boiling points are separated, which mixture may include inconsequential proportions of additional components, to stabilize the purity of the highest boiling point product, comprising utilizing the changes in the temperature differential between a level in the column where the highest boiling point product is at the maximum purity and a second level in the column in the neighborhood where the concentration of the intermediate boiling point tertiary component is beginning to decrease from a maximum and the concentration of the lowest boiling point component is low but is beginning to increase to control the rate of withdrawal of the highest boiling point product.

7. The method of controlling the rate of withdrawal of oxygen product of an air fractionating column to stabilize the purity of the oxygen product withdrawn from the column, comprising utilizing the changes in the temperature differential between a level in the column where the oxygen product is at the maximum purity and a second level in the column in the neighborhood where the argon concentration is beginning to drop from a maximum and the concentration of the nitrogen is low but is beginning to increase to control the rate of withdrawal of the oxygen product.
